UNITED STATES PATENT OFFICE

153,736

DESIGN FOR A SLIDE FASTENER REPAIR TOOL

Kurt Stern, Chicago, Ill.

Application September 3, 1948, Serial No. 148,452

Term of patent 3½ years

(Cl. D54—13)

To all whom it may concern:

Be it known that I, Kurt Stern, a citizen of the United States, residing at Chicago, in the county of Cook and State of Illinois, have invented a new, original, and ornamental Design for a Slide Fastener Repair Tool, of which the following is a specification, reference being had to the accompanying drawing, forming a part thereof.

Fig. 1 is a perspective view of the slide fastener repair tool, embodying the new design;

Fig. 2 is a top plan view;

Fig. 3 is a side view;

Fig. 4 is a bottom view;

Fig. 5 is a front end view taken on line 5—5 of Fig. 3; and

Fig. 6 is a rear end view taken on line 6—6 of Fig. 3.

I claim:

The ornamental design for a slide fastener repair tool, substantially as shown.

KURT STERN.
